Patented Apr. 2, 1929.

1,707,395

UNITED STATES PATENT OFFICE.

STEPHEN J. HAYDE, OF KANSAS CITY, MISSOURI, ASSIGNOR TO AMERICAN AGGREGATE COMPANY, OF KANSAS CITY, MISSOURI, A CORPORATION OF MISSOURI.

METHOD OF BURNING ARGILLACEOUS MATERIAL AND PRODUCT RESULTING THEREFROM.

No Drawing.

Application filed February 10, 1920. Serial No. 357,761.

My invention relates to the manufacture of light weight aggregate for concrete and other purposes, but more especially for concrete for the making of sewer pipe, tile, terra cotta, paving blocks, brick, bodies or forms for ship building and like molded articles, also mortar for brick and masonry work, stucco, plastering and paving, from a raw material of an argillaceous or clayey character and which, upon being burned, will harden and form a clinker or mass which is subsequently crushed, and then mixed with a suitable cementitious material and the mixture molded into proper form and permitted to harden; and particularly to the burning step or operation to which such material is subjected in order to produce the hard mass or substance which, when crushed, forms the basis of the article produced, and the particles of which crushed material are cemented together by the cement employed to thereby produce the finished product.

The present case is in part a continuation of an application filed February 28, 1919, Serial Number 279,906.

By my process the basic raw material, in substantially the same condition as that in which it comes from the original deposit, may be broken up or separated into any suitable sizes, for example, it may be broken so as to pass a screen of about a four inch mesh, it having been found that screened to approximately this size good results are secured; or, if desired, the material may be otherwise formed into appropriate sizes. The material thus prepared is then burned in any suitable kiln at a temperature in excess of 1500° Fahrenheit, it having been found that by employing the temperatures specified, the effect is to first expand the material, destroy the organic matter therein, and produce a hard mass or clinker of cellular formation.

The temperature and the burning period are, it will be understood, to be so regulated as to give the hard cellular formation without carrying the burning to such an extent as to vitrify the material, although, of course, during the period in which the large pieces are expanded and converted into the hard cellular-like formation referred to, small particles, which may be broken from the larger pieces and subjected to burning, may vitrify, the process contemplating, however, continuing the burning step only for a length of time

sufficient to insure that the bulk of greater proportion of the product will be in expanded or cellular condition, for if the burning is continued beyond a certain period and temperature, the result will be to vitrify all of the material.

I have found a maximum amount of the product and a more uniform product is obtained if the material is subjected to the highest temperature employed in burning, at the very beginning of the burning process.

This subjecting of the material to intense heat at the beginning of the burning action rapidly softens and fuses the same to a degree, and tends to sear over the exterior surface of the material being burned, while at the same time any organic matter in the material is consumed and the water present within the material is driven off therefrom with more or less violence, and the extremely rapid expansion of the steam and gases produced by the action of the heat expands the material and produces a clinker having an internal cellular structure within the same characterized by the presence of an extremely large number of minute cells or cavities within the body or mass of the material so burned.

The cellular structure having been once produced will be present in the product at the end of the burning operation, and, when the burned material is crushed, the particles thereof will have a cellular structure, and a rough and pitted surface. The cementitious material subsequently mixed with the crushed particles will therefore obtain a firm hold upon the roughened exterior surface thereof, and form a firm bond between them and the cementing material, thus providing a stronger union between the particles and a stronger finished product than would otherwise be the case.

Furthermore, the cellular structure of the particles which are cemented together secures or results in a less dense finished product, because the material, while of a cellular formation, is not of a porous or absorptive character or nature.

The raw material subjected to the improved burning process wherein my invention consists may be clay, shale, shale rock or any other argillaceous material.

The high temperature to which the material is subjected at the beginning of the

burning process will vary with different materials, and may vary with a given material with an accompanying variation in degree of the effects hereinbefore pointed out which are 5 secured in my process. Generally speaking, a temperature of from not less than 1500, and generally 1700 degrees, to approximately 2500 degrees Fahrenheit will be suitable for most raw materials, and such a temperature will 10 secure the results hereinbefore pointed out to a marked degree.

After the material has been burned as described, and cooled sufficiently, it is crushed to produce relatively coarse particles, which 15 will pass through a screen of any desired size, and finer particles graduated down to impalpable dust. The coarser particles are then mixed with some of the finer particles to produce an aggregate, which when mixed 20 with cement will, by the addition of water, be converted into a concrete that is particularly adapted for the uses and purposes hereinbefore stated.

I regard my invention as comprehending 25 and including (1) the improved method of burning an argillaceous material as hereinbefore explained; (2) the hardened cellular product thus obtained in performing the burning process; (3) the crushed material 30 made up of particles having rough and pitted exterior surfaces and an internal cellular structure, (4) the concrete mixture obtained by mixing such crushed material with cementitious material, and (5) the product obtained by treating such mixture of crushed 35 material and cementitious material with water and permitting the mixture to harden within a suitable mold, or otherwise shaping the mixture into the form of the finished 40 article or structure, and have so claimed my invention in the following claims.

It will be understood that while I have described a particular and novel process by 45 which the novel product may be produced, and that the best and only process now known to me, I do not limit myself to the specific method set forth for making this new product, as such novel product, it is conceivable, may be secured by other and different 50 methods of treatment. Furthermore, such variations of the particular process herein set forth as are within the skill of the operator and do not depart substantially from the method herein set forth, are to be regarded 55 as within the scope of my invention.

I am aware that it has been heretofore proposed to manufacture a porous material by heating pieces or plates of slate and sawing the calcined material into the shapes desired 60 or preparing it for mixture with a binding material and molding such mixture. My invention, however, contemplates an initial division of the material to be treated into a relatively fine condition and the product 65 which I obtain is quite different from the

calcined slate referred to. Further, my improved product may be obtained from a non-laminated argillaceous material.

It has also been proposed to mix clay and suitable fuel and then by burning out the fuel 70 obtain a cellular material which may be mixed with cement to form concrete. Such process and the product thereof are quite different from my invention in which the material treated may be used in its natural 75 state, unmixed with any other substance; and by which the desired product is obtained by expansively burning such natural material, preliminarily subdivided into a relatively fine condition, and crushing the 80 burned product.

By the term "expansively burned" as employed in certain of the appended claims is meant the product obtained by subjecting a natural, or raw, material to treatment, where 85 by the material will be rendered of cellular form by the expansive action of gases and moisture contained therein due to the sudden application of a relative high temperature as distinguished from the combustion of the 90 fuel constituent of a mixture of fuel and clay.

Having thus described and explained my invention, I claim and desire to secure by Letters Patent:

1. The process of burning an argillaceous 95 material to produce an aggregate for the purposes specified which, consists in subjecting said material to the highest temperature employed in burning the same at the beginning of the burning process.

2. The process of burning an argillaceous material to produce an aggregate for the purposes specified which, consists in subjecting said material to the highest temperature employed in burning the same at the beginning 105 of the burning process, and completing the burning of said material at a lower temperature.

3. The process of burning an argillaceous material which consists in subjecting said 110 material to a temperature in excess of 1500 degrees Fahrenheit at the beginning of the burning process, and completing the burning of said material at a lower temperature.

4. The process of burning an argillaceous 115 material which consists in subjecting said material to a temperature ranging between approximately 1500 degrees Fahrenheit to approximately 2500 degrees Fahrenheit at the beginning of the burning process, and 120 completing the burning of said material at a lower temperature.

5. The process of producing material for use in making molded bodies or articles, which consists in burning an argillaceous material, 125 the material being subjected at the beginning of the burning operation to the highest temperature employed and the burning being completed at a lower temperature, and crushing the burned material.

6. An aggregate produced by burning an argillaceous material in its natural state and in a relatively finely sub-divided condition, and crushing the burned product, the particles comprising the aggregate being characterized by being free from laminations and the presence within the body thereof of a large number of minute cavities or cells. 55
7. An aggregate produced by burning argillaceous material in a relatively finely sub-divided condition and crushing the burned product, the particles composing the aggregate being characterized by being free from laminations and the presence within the body thereof of a large number of minute cavities or cells produced by the expulsion of moisture and gaseous constituents originally present in the said material. 60
8. An aggregate produced by burning argillaceous material and crushing the burned product, the particles composing the aggregate being characterized by being free from laminations and the presence within the body thereof of a large number of minute cavities or cells produced by the expulsion of moisture and gaseous constituents originally present in the said material. 65
9. An aggregate comprising a mixture of coarse and fine non-laminated pieces of crushed expansively burned argillaceous material, the larger pieces having rough and pitted exteriors and minute cells or cavities within their bodies. 70
10. The herein described process of producing an aggregate for the purposes specified and the particles of which are free from laminations comprising dividing a raw argillaceous material into relatively small pieces, burning such finely subdivided material, and crushing the burned product. 75
11. The crushed, expansively burned, argillaceous material herein described composed of non-laminated particles having rough and pitted exterior surfaces, and the interiors of which particles contain a large number of minute cells or cavities. 80
12. The process of making a non-laminated aggregate suitable for the manufacture of molded articles which comprises expansively burning a relatively finely subdivided raw unmolded argillaceous material, and crushing the burned material. 85
13. An aggregate or material for use in manufacturing molded articles comprising crushed, expansively burned argillaceous material, said aggregate being free from laminations. 90
14. A material for use in manufacturing molded articles comprising a mixture of crushed, expansively burned argillaceous material, said burned material being free from laminations, and cementitious material. 95
15. The method of making a concrete material which consists in burning an argillaceous material in a relatively finely subdivided condition to produce particles characterized by the presence within the body thereof of a number of minute cavities or cells, crushing the burned material into fine and coarse pieces free from laminations, and mixing a mixture of said fine and coarse pieces with a cementitious material. 100
16. A non-laminated aggregate or material for use in manufacturing molded articles comprising crushed, expansively burned, argillaceous material. 105
17. A concrete block or structure, consisting of cement, and an aggregate of vesicular material free from laminations or planes of cleavage resulting from subjecting suitable earthy material containing compounds capable of evolving gases to sufficient heat to incipiently fuse the material and render it vesicular, as and for the purpose set forth. 110
18. As an article of manufacture, a crushed cellular cement aggregate comprising expanded argillaceous material free from laminations or planes of cleavage. 115
19. A non-laminated aggregate produced by burning argillaceous material in its natural state, to convert such material to a vesicular, expanded, condition by expansion of moisture and gaseous constituents originally present in the material, and then crushing such burned material. 120
20. A molded block or structure consisting of cement, and an aggregate comprising particles free from laminations and produced by burning an argillaceous material in its natural state to render it vesicular by expansion of moisture and gaseous constituents originally present in the material, and crushing such burned material. 125

In testimony whereof I have hereunto set my hand.

STEPHEN J. HAYDE.
